UNITED STATES PATENT OFFICE.

J. W. WILCOX, OF NEW YORK, N. Y.

IMPROVED BOX.

Specification forming part of Letters Patent No. 83,812, dated November 3, 1868.

To all whom it may concern:

Be it known that I, J. W. WILCOX, of city of New York, in the county of New York and State of New York, have, as I believe, invented a new and useful Mail Sample-Box, which I call "The Grocer's U. S. Mail Sample-Box;" and I do hereby declare the following to be a full and exact description of the same, reference being had to the drawings that accompany and form a part of these specifications.

Figure 1, view of the pattern before folding; Fig. 2, the stock of one of the boxes partly folded; Fig. 3, one with the lappet just entering its pocket; Fig. 4, longitudinal bisection of one of the boxes; Fig. 5, view of one of the boxes ready for the mail.

Letter A represents the face or wide sides of the box; letter B, the two narrow sides; letter C, the bottom or fixed end; letter D, the lappet for opening and closing; letter E, the pocket for the reception of the lappet; letter f, stiffening-pieces firmly attached in place; letter g, strengthening-pieces or lappets; letter h, strengthening-pieces for upper corners; letter i, supplemental lappets closing in the mouth of the box with the lappet D; letter j, opening into the pocket; letter l, band for keeping the box closed.

The manner of cutting out the material will be readily understood from the drawings.

In folding I first form the pocket E by turning the piece d over and gluing down the edge thereof, as indicated by the red dotted lines in Fig. 1, after being creased. I next raise the side B' and turn up A, as in Fig. 2, bringing up the lappets g and gluing them securely; then bring the two sides A and A' parallel, and turn up the pieces B', turning in the pieces h, and the box assumes shape, as in Fig. 3.

Fig. 4 will show the positions of the several

parts when the box is finished and closed, and how the pieces g, the double sides B and B', and lappets h, all serve to form a very strong box.

The object of my invention is to provide an economical and very light yet strong box, and one that will bear much rough usage, to be carried in the mail for conveying samples of tea, coffee, sugar, spices, and other like articles, and many other things that require protection of this nature in order to go safely through the mails.

The peculiarity of my invention consists in the manner or shape in cutting, as also in folding the parts together, securing great strength with a very small amount in weight of stock—matters of much consequence when safety to the articles carried and economy in postage are considered.

The close pocket E, the lappet D, and supplemental lappets i, all conspire to make the box very close, so a liquid could with difficulty escape.

The material for making these boxes may be pasteboard or any other suitable material.

What I claim as of my invention, and desire to secure by Letters Patent, is—

1. The supplemental lappets i, in connection with the lappet D and strengthening-folds h, substantially as described and set forth.

2. The above, in combination with the pocket E, as and for the purposes specified and set forth.

In testimony whereof I have signed my name to this specification in the presence of two subscribing witnesses.

J. W. WILCOX.
